UNITED STATES PATENT OFFICE.

JOSEPH E. RUZYCKI, OF HOLYOKE, MASSACHUSETTS.

PORABLE ARMY-SHIELD.

1,246,662.

Specification of Letters Patent. Patented Nov. 13, 1917.

Application filed October 7, 1916. Serial No. 124,271.

To all whom it may concern:

Be it known that I, JOSEPH E. RUZYCKI, a subject of the Emperor of Austria, residing at Holyoke, in the county of Hampden and State of Massachusetts, have invented a new and useful Portable Army-Shield, of which the following is a specification.

My invention relates to improvements in shields for soldiers on the field of battle, 10 and resides in a skeleton frame mounted on wheels and packed or stuffed with cotton, cotton waste, or other fibrous material which is comparatively light in weight, yet is capable of resisting and absorbing as it 15 were bullets fired into the same, the vehicle or carriage thus formed being provided with one or more covers or masks for the purpose of disguising the same, and equipped with one or more foot guards of special construction, with rear-end side guards preferably 20 of fibrous material faced with metal, and with such accessories as may be needed or desired, mention being made particularly of a handle and push bars, a seat, a machine- 25 gun, and a periscope, all as hereinafter set forth.

The primary object of my invention is to produce a shield for a small company of soldiers, which shield is capable of affording 30 ample protection to the soldiers behind the same, and at the same time is so light that it can be moved without difficulty in any direction, and over obstacles even, by said soldiers.

35 A further object is to provide such a shield with means of disguise whereby the same at a sufficient distance is practically indistinguishable from the surrounding landscape.

Although the shield is adapted to carry a 40 machine-gun, or even more than one such gun, and to protect the machine-gun squad, said shield might be used equally well by a rifle squad, the machine gun being omitted, or rifles may be used as auxiliary offensive 45 weapons in connection with the machine-gun. Thus the range of efficiency of the shield is not limited.

The periscope is in most cases a valuable 50 and desirable adjunct, but may be dispensed with.

By providing the shield with loosely suspended foot guards that can be drawn up out of the way, as I have done, I am able, 55 not only to employ wheels of sufficiently

large diameters, but to locate the body portion of the shield well above the ground, so that the shield can be most readily moved about, both in and out of action.

Power of resistance to small-arms fire, and convenience, ease and freedom in the 60 matter of mobility are of primary importance in a portable army shield, and these two factors are found in fully developed form in this shield.

Other objects and advantages will appear 65 in the course of the following description.

A preferred embodiment of the invention, whereby I attain the objects and secure the advantages of the same, is illustrated in the accompanying drawings, and I will proceed 70 to describe the invention with reference to said drawings, although it is to be understood that the form, construction, and arrangement, etc. of the parts in various aspects are not material and may be modified 75 without departure from the spirit of the invention.

In the drawings, in which like numerals designate like parts throughout the several views, Figure 1 is a top plan of a shield that 80 embodies a form of my invention as aforesaid; Fig. 2, a side elevation of said shield; Fig. 3, a front end elevation of the same; Fig. 4, a rear end elevation thereof; Fig. 5, a central longitudinal vertical section 85 through the shield, and, Fig. 6, a side elevation of the shield, showing one of the covers or masks in place over the body of said shield.

The main portion or body of the shield 90 has an approximately horizontal bottom, approximately vertical sides, an approximately vertical rear end, and a slanting top which extends from the front end of the bottom or base to the top of the back end. And as 95 here represented said body comprises a skeleton frame which is mounted on a pair of large rear wheels 1 and a pair of smaller front wheels 2, a mass filling of comparatively light-weight bullet-resisting material, 100 and a water-proof fabric cover 4. This body is provided with a front-end nose-piece 3, an armor-plate hood 5, rearwardly extending arms 6—6 connected at their back ends by a cross-bar 7 to form a handle with which 105 to push and pull the shield about, side wings 8—8 at the rear end of the body, and one or more foot guards.

The aforesaid skeleton frame consists of a pair of longitudinal bottom beams 9, a pair 110

of transverse beams 10 which connect said beams 9 at points somewhat remote from the ends of said beams 9, an upright 11 rising from each of said beams 9 at the rear end thereof, inclined beams 12—12 which extend from the extreme front ends of said beams 9 rearwardly to and a little beyond the upper terminals of the uprights 11, and a cross beam 13 between said uprights at the top and contiguous parts of said beams 12, together with one or more longitudinal supports 14 between said beams 10. A lug 15 rises from each beam 9, and this lug has a trunnion 16 upon which one of the wheels 1 is mounted. A portion of the filling mass or padding is represented as being torn away, in Fig. 5, to show the lug 15 which would otherwise be hidden, and still another portion of said padding is represented as being torn away, in said view, so that a part of the upright 11 behind said lug may be seen in full. The front wheels 2 are mounted on an axle 17 which is journaled at 18—18 beneath the beams 9 near their front ends.

The trunnions 16 are so located that the shield can be tilted easily on the wheels 1 so as to raise the wheels 2 clear of the ground. In other words, the plane of the axis of the wheels 1 is only a very little behind the transverse center of gravity of the shield. By mounting the body of the shield in this manner, I am able to lift the front wheels from the ground and move the shield about with the greatest freedom on the rear wheels.

The nose-piece 3 extends between and is secured to the front ends of the beams 9 and 12, and serves to protect from bullets whatever is behind such nose-piece. The upper portion of the nose-piece 3 is supported on enlargements 19—19 of the beams 12, which enlargements are arranged and adapted to give to such portion a greater inclination than that of said beams, so that bullets striking said portion are deflected more sharply upward from their course, and protection is afforded to a greater area behind the nose-piece.

The resistance filling or padding which I prefer to employ consists of cotton and cotton waste, as represented at 20 in Fig. 5, stuffed into coarse fabric cases, as represented at 21 in said view, to form units or pads 22. It is more convenient and satisfactory to use the filling in the form of units or pads, owing to the facility with which said filling in that form can be placed in position in the frame, and more especially to the readiness with which any portion of the filling, which has been rendered useless or unsafe during an action, can be replaced after such action.

The pads 22 are placed in the frame on the beams 9 and 10 and the supports 14, and completely fill the space in said frame, such

pads being flush with the outer sides of said beams 9 and the beams 12, the outside vertical planes of said beams 10, and the upper surfaces of said beams 12, entering under the beam 13 and between the uprights 11. 70 Thus is formed a defensive element having great bullet-resisting power and yet being in comparison very light in weight.

The cover 4 is drawn tightly over, under and on all sides of the pads 22 and secured 75 to the frame. The purpose of the cover 4 is to protect the fibrous filling from the elements and keep it dry.

The hood 5 is secured to the beams 12 and the uprights 11, and flares upwardly at the 80 rear end, above the back portion of the top of the body proper, to provide an inclosed and protected space for a machine-gun 23. The shield 5 has a shelf 24 within to assist in supporting the machine-gun 23, and is 85 pierced at 25 for the passage of the barrel of said gun.

A seat 26 may be provided for the soldier who operates the machine-gun 23. The seat 26 is located at the required elevation behind the pads 22, so that the occupant has the machine-gun within convenient reach, and said seat may be supported by means of two bent rods 27 and 28 forced into said pads from the rear. This means enables the seat 90 to be easily and quickly removed and replaced, for the purpose of adjustment or any other purpose.

The arms 6 are secured at their front terminals to the protruding rear terminals of 100 the beams 9, and there is a brace 29 between said arm terminals, which may serve as a push bar, auxiliary to the cross-bar 7, and as a step in mounting to and descending from the seat. The handle is provided further 105 with an adjustable push bar 30. The bar 30 is held in place on the arms 6 by means of pins 31—31 which pass through holes in said bar and arms. The holes for the pins 31 in the arms 6 are represented at 32, in 110 Fig. 1, and there is a plurality of pairs of such holes so that the bar 30 can be variously located on the arms 6. Ample facilities are afforded, by the arms 6 and their connecting and attached parts, for the number of men 115 required to propel the shield to grasp such arms and parts. The cross members 7, 29 and 30 are all in the rear of the pads 22.

A periscope is represented at 33. The periscope 33 is located behind the pads 22, at 120 one side of the seat 26, rises through the hood 5, and is held in place by said hood and an eye-rod 34 forced into said pads from the rear. Below as a part of the periscope 33 is a base member 35 which is fastened to 125 the back of the cover 4. The functions of the periscope are well understood and need no explanation here, and the same is true of the machine-gun.

The wings 8 afford lateral protection to 130

the occupant of the seat 26 and to all who may be between said wings. They are, for the sake of lightness, made of similar materials as and made up in a similar manner to 5 the pads 22, except that they have armor-plate facings 49. Each padded wing 8 is mounted behind one of the uprights 11 and between the protruding terminal portion of the beam 9 under such upright, or the arm 6 10 supported on said terminal portion, and the protruding terminal portion of the beam 12 above, being fashioned at the base to fit over said arm and the contiguous end of the bar 29, and at the top to receive said terminal 15 portion of said beam 12. Other securing means for the wings 8 may be provided, such as straps and buckles as indicated at 36.

Inasmuch as the body of the shield is carried by the wheels 1 and 2 well above the 20 ground, it is necessary to protect the feet of the soldiers behind the shield, when in action, and to this end I provide one or more transverse guards 37 which depend from said body. The guards 37 are hung beneath 25 the body of the shield in such a manner that they drag on the ground or trail slightly when the shield is moved either forward or backward. Preferably the guards 37 are so arranged that they can be turned up out of 30 the way when not required for active use. Each guard 37 has a pair of trunnions 38, and these trunnions are journaled in bearing brackets 39 that depend from the beams 9. There are vertical slots 40 in the brackets 39, 35 for the trunnions 38, to afford the necessary lost motion or freedom, when the direction of the shield is reversed, so that the wheels 1 and 2 will not be lifted off of the ground by the guards 37 at such time. Thus, when the 40 shield is pushed forward, the guards 37 trail behind, as best shown in Fig. 2, with their trunnions 38 in the bottoms of the slots 40, but upon drawing said shield backward said trunnions first rise in said slots as said 45 guards fulcrum on the ground and change their slant, and then said trunnions drop to occupy the bottoms of said slots again. Corresponding movements take place when the direction of the shield is again changed. 50 The normal obliquity of the guards 37, on either side of the vertical planes of the trunnions 38, is slight, but when said guards pass over obstructions in their path they are necessarily caused momentarily to assume a 55 greater obliquity, which being free to swing they can readily do.

The guards 37 may be made comparatively light by employing armor-plate shells and filling and backing such shells with 60 padding of fibrous or equivalent material, such as is used in the construction of the body and the wings 8. The aforesaid padding is represented at 41.

As a simple and convenient means for 65 drawing the guards 37 up and clear of the

ground and securing them, cords 42 and cleats 43 may be provided. The cords 42 extend from the back sides of the guards 37 up through the body to the cleats 43, which latter are attached to the back of said body. 70 The cords 42 from the front and middle guards are passed through guides 44 in the underside of the body, such guides being so positioned as to prevent either of said cords from being interfered with by the guard behind. 75

Any guard 37 can be swung up and fastened by drawing its cord 42 rearwardly and securing said cord to the cleat 43 provided therefor—see Fig. 6. And any guard 80 can be lowered into operative position by unfastening its cord and permitting such guard to swing freely through the arc which the guard describes when the direction of the shield is changed. The guards are swung 85 up and secured by means of the cords 42 and cleats 43 whenever the shield is propelled through a section of country where said shield is not subjected to gun fire, as a rule, because of the greater facility with 90 which said shield can be moved while said guards are off of the ground.

The protection afforded by a plurality of shields 37 is much greater than would be that afforded by a single shield, especially 95 if the latter were as light as is the type of shield that I prefer to employ.

In taking the shield through hostile territory or adjacent to such territory, where it is important that the same shall not be 100 seen by the enemy, it is desirable, not to say necessary, that the shield be disguised as much as possible. As a means of disguise for the shield at such times I provide one or more covers or masks 45. These 105 masks are prepared to conform to a greater or less extent, in color or tint at least, with the territory through which the shield is to be taken, so that the particular mask employed at a given time will blend in some 110 degree with the surrounding landscape. Each mask 45 is designed to be used with some particular type of landscape different from that with which either of the other masks is designed to be used. A spring 115 roller 46, of ordinary construction, is mounted behind the nose-piece 3 in the space between said nose-piece and the front pads 22, such roller being journaled in the beams 9, and one of the masks 45 has its front or 120 inner end secured to such roller. When not in use the masks 45 are rolled on the rollers 46 and confined in the aforesaid space, one rolled mask behind the other. Cords 47 extend from the rear or outer ends of the 125 masks 45, when the latter are rolled up, to the rear of the body, the rear ends of said cords being fastened to headed studs 48—48 which project from the outer sides of the beams 12 back of the hood 5. The cords 47 130

pass from the under sides of the rolled masks, up over the front of the nose-piece 3 and the top of the body, to the studs 48.

When it is desired to cover the shield with 5 any one of the masks 45, the required mask is unrolled through the medium of the cords 47 attached thereto, and drawn and spread over the top and sides of the body, substantially as shown in Fig. 6, being fastened to 10 the studs 48 and held thereby against the resiliency of the spring roller 46 from which said mask is unwound. The general appearance of the shield is thus made to assume that of the country through which the shield 15 is passing or in which it is located. Upon releasing the mask from the studs 48 and folding the side flaps onto the top portion of said mask, the latter is ready to be and is rewound on its roller 46, the action of 20 said roller being automatic, as is the case with a roller of this type.

I have shown three masks 45 with their rollers and cords, and the same number of guards 37 with their appurtenances, but 25 such number may be increased or decreased in either case.

From the foregoing the manner in which the shield and its attachments and accessories are operated will be fully understood. 30 It is clear, of course, that the shield, with the guards 37 down, is run forward into action by a squad of soldiers behind the same, and that the machine-gun 23 is fired by a soldier on the seat 26, an officer using 35 the periscope 33 to assist him in directing the men. Meanwhile the soldiers are within the protection afforded by the shield.

The masks 45 can be unwound from their rollers 46 or permitted to be rewound thereon by means or through the medium of the cords 47, from a position behind the body of the shield.

What I claim as my invention, and desire to secure by Letters Patent, is—

45 1. A portable army shield comprising a frame mounted on wheels and having top, bottom, and side members, and a filling of comparatively light material of a fibrous nature in said frame between said members 50 thereof.

2. A portable army shield comprising a padded frame, front and rear wheels for the same, said padded frame being between said rear wheels.

55 3. A portable army shield comprising a skeleton frame mounted on wheels, and padding introduced into and supported by such frame back of the front end thereof.

4. A portable army shield comprising a 60 vehicular frame stuffed with bullet-resisting material back of the front end.

5. A portable army shield comprising a vehicular frame stuffed with bullet-resisting material, and provided at the front end with

a nose-piece plate, said material having at 65 the top an upward inclination from front to rear.

6. A portable army shield comprising a vehicular frame stuffed with bullet-resisting material, and provided at the rear end with 70 a metal hood, said material having at the top a downward inclination from back to front.

7. A portable army shield comprising a 75 vehicular frame stuffed with bullet-resisting material, and provided at the front end with a nose-piece plate, and at the rear end with a metal hood.

8. A portable army shield comprising a 80 vehicular frame stuffed with bullet-resisting material back of the front end, and having side wings at the rear end.

9. A portable army shield comprising a 85 vehicular frame stuffed with bullet-resisting material back of the front end, and having padded side wings at the rear end.

10. A portable army shield comprising a 90 vehicular bullet-resisting body, and a foot guard suspended to be swung on its axis and to move radially thereto beneath such body. 90

11. The combination, in a portable army shield, with a vehicular bullet-resisting body, of a roller mounted in said body, and a mask attached to said roller and adapted to be drawn off and spread over said body, such 95 mask blending in a greater or less degree, with a given type of landscape.

12. The combination, in a portable army shield, with a vehicular skeleton frame, padding in such frame, and a nose-piece at the 100 front end of such frame, of a roller journaled in said frame between said nose-piece and padding, and a mask, for said frame, nose-piece and padding, attached to said roller. 105

13. The combination, in a portable army shield, with a vehicular skeleton frame, padding in such frame, and a nose-piece at the front end and a hood at the rear end of such frame, of a roller journaled in said frame 110 between said nose-piece and padding, and a mask, for said frame, nose-piece, padding and hood, attached to said roller.

14. The combination, in a portable army shield, with a vehicular frame stuffed with 115 bullet-resisting material, of a roller of the self-winding type journaled in said frame, a mask attached to and normally wound on said roller, and means to unwind said mask from said roller. 120

15. The combination, in a portable army shield, with a vehicular skeleton frame stuffed with bullet-resisting material, of a seat provided with supporting means that are adapted to be forced into such material 125 at the rear end thereof.

16. A portable army shield comprising a vehicular skeleton frame, and a filling, con-

sisting of bullet-resisting material contained in fabric cases, in said frame, such filling extending from the rear end of said frame forward.

- 5 17. A portable army shield comprising a vehicular skeleton frame filled with bullet-resisting material, such material extending from the rear end of said frame forward, and a waterproof cover over such frame and material.
- 10 18. A portable army shield comprising a vehicular skeleton frame, and units or pads

of bullet-resisting material in said frame back of the front end thereof.

19. A portable army shield comprising a 15 vehicle skeleton frame, units or pads of bullet-resisting material in said frame back of the front end thereof, and a water-proof cover over such frame and pads.
